UNITED STATES PATENT OFFICE.

HENRI HALDY, OF WALTHAM, MASSACHUSETTS, ASSIGNOR TO STARK TOOL COMPANY, OF WALTHAM, MASSACHUSETTS, A CORPORATION OF MASSACHUSETTS.

TOOL POST.

1,409,099.

Specification of Letters Patent.

Patented Mar. 7, 1922.

Application filed March 10, 1920. Serial No. 364,772.

To all whom it may concern:

Be it known that I, HENRI HALDY, a citizen of the United States, residing at Waltham, in the county of Middlesex and State 5 of Massachusetts, have invented an Improvement in Tool Posts, of which the following is a specification.

This invention relates to tool-posts for lathes and has for its object to improve the 10 construction and facilitate the manipulation of the tool-post and, specifically, to provide a tool-post with means admitting of clamping the tool at various inclinations with respect to the slide rest thereon and with an 15 enclosed and thereby protected binding screw.

In carrying out my invention, I provide the tool-post with a lower base and clamping-member and an upper movable clamping-member disposed about and enclosing and thereby protecting the binding-screw. The two clamping-members are arranged to receive and clamp a tool between them at 20 one side of the binding-screw. I provide 25 clamping-pressure compensating means in the form of a resilient spring between the two members on the opposite side of the binding-screw from the tool-clamping portion of the tool-post whereby to relieve the 30 tool-post from cramping or bending strains and I also provide a guiding-means between the two members whereby, assisted by the binding screw, the upper clamping-member may move toward or away from the lower 35 clamping-member and be restrained from angular movement; and this comprises a second object of my invention.

Fig. 1 is a side elevation of a tool-post embodying my invention,

40 Fig. 2 is an end elevation of Fig. 1,

Fig. 3 is a transverse sectional elevation of the tool-post,

Fig. 4 is a plan view of the base member with the movable clamping-member removed,

45 Fig. 5 is a sectional detail along line 5-5 of Fig. 4,

Fig. 6 is a plan view of the lower face of the movable clamping member.

As here shown the tool-post constructed 50 in accordance with my invention comprises the lower clamping or base member 10 and the upper clamping-member 11 between which and to one side of the binding screw 12 the tool is adapted to be clamped.

55 The base member 10 comprises a prefer-

ably square block of substantial thickness having a relatively large lower bearing face to engage the face of the slide rest 13 whereby the tool-post may be firmly supported thereabove. Said block has the hole 14 60 therethrough in which the vertical binding-screw 12 is disposed and extended thereabove to support the movable clamping member.

The base-member 10 is formed with a recess 16 therein having a circular bottom at 65 one side of the binding-screw and a clamping-jaw 17 having the flat top face 17^a and the corresponding circular lower face 17^b is movably received therein whereby to form a self-centering seat for the tool and admit of 70 holding the tool at various inclinations with respect to the face of the slide-rest. A screw 18 loosely extended through the elongated slot 19 in said base member into said jaw serves to retain the jaw in place and permit 75 its necessary sliding movement.

A guide-pin 20 is fixed in said base-member on the opposite side of the binding-screw from the clamping-jaw and extends thereabove to receive and guide the upper clamping-member.

The upper-clamping member 11 is formed as a cylindrical block having the central hole 21 therethrough in which the binding-screw is extended and on which it is supported and 85 guided. A cylindrical recess 22 is formed in the lower portion of said clamping-member on one side of the binding-screw in which the guide-pin 20 of the base-member is received and by which it is also guided 90 and supported. A compression spring 23 is received in said recess above said guide-pin and engages the top of said pin and the bottom wall of the recess. When a tool is clamped in the tool-post the spring is adapted to be compressed thereby to support the upper clamping-member against the clamping pressure.

The spring, in effect, forms a yielding fulcrum for the upper clamping-member and 100 counterbalances the clamping pressure on the tool and thereby reduces the tendency of the clamping member 11 to tilt laterally about the bolt 12 as a fulcrum.

The upper clamping-member is formed 105 with a tool-receiving recess extending from end to end of it on the opposite side of the binding screw from the spring, having the flat vertical face 24 against which the tool is adapted to rest. A clamping pin 25 is 110

fixed in the upper face of said recess over the clamping-jaw 17 and in line with the spring and binding screw. Said pin has the enlarged and spherically-shaped clamping head 25^a adapted to forcibly engage the tool. By reason of the spherically shaped head 25^a and the self-seating clamping-jaw 17 a tool may be securely gripped therebetween at an inclination with the face of the slide 10 rest as indicated in the dotted lines, Fig. 1.

Said binding screw 12 extends above the upper clamping member 11 and is threaded in the recess 26 of the nut 27 by which said upper clamping-member is forced into engagement with the tool.

In clamping a tool in the tool-post the rotation of said nut 27 moves the upper clamping-member into engagement with the tool and also compresses the spring 23, and the spring pressure assists materially in supporting the clamping member against lateral or rocking movement; and also serves to raise the clamping-member away from the tool when the nut 27 is reversely rotated.

25 I claim:

1. A tool-post for lathes comprising a binding-screw and upper and lower clamping-members movable thereon to engage and clamp a tool between them having tool-engaging means on one side of the binding screw, and guiding means extended between said clamping-members on the other side of the binding-screw including resilient means arranged yieldingly to support the upper 30 clamping-member above the lower clamping-member and reduce its tendency toward lateral deflection under the clamping pressure.

2. A tool-post for lathes comprising a binding-screw, upper and lower clamping members movable thereon to engage and clamp a tool between them each having tool-clamping means on one side of the binding-screw, a guide-pin extended above the lower 40 screw, a guide-pin extended above the lower 45 clamping-member on the opposite side of the binding-screw, said upper clamping-member having a recess in which said pin is slidably received, and a compression spring disposed in the recess between the end of said pin and 50 the bottom of the recess.

3. A tool-post for lathes comprising a binding-screw, upper and lower clamping-members movable thereon to clamp a tool between them, said lower clamping-member 55 having a slot with a circular bottom in its

upper face on one side of said binding-screw, a clamping-jaw having a circular bottom face movably received in said recess, said upper clamping-member having a tool-receiving recess extended from end to end of 60 it, on the same side of the binding-screw, a clamping pin having a spherically-formed tool-engaging head fixed in the upper wall of the recess in said upper clamping-member above said clamping jaw, and clamping-pressure compensating means connecting said two clamping-members on the opposite side of said binding-screw.

4. A tool-post for lathes comprising a binding-screw, upper and lower clamping-members movable thereon to clamp a tool between them, said lower clamping member having a slot with a circular bottom in its upper face on one side of said binding screw, a clamping-jaw having a circular bottom 70 face movably received in said recess, said upper clamping member having a tool-receiving recess extended from end to end of it on the same side of the binding-screw, a clamping pin having a spherically-formed 75 tool-engaging head fixed in the upper wall of the recess in said upper clamping-member above said clamping jaw, a guide-pin fixed to and extended above said lower clamping-member on the other side of said binding-screw, said upper clamping-member having a recess in which said pin is slidably received, and a compression spring disposed in 80 said recess and engaging the bottom wall of the recess and the top of said pin.

5. In a tool post for lathes, upper and lower clamping members adapted to clamp a tool between them, and means to clamp the tool at various inclinations therebetween, comprising a clamping-pin having a spherically formed clamping-head carried by said upper clamping-member, said lower clamping member having a slot with a circular bottom wall therein below said clamping-pin, a clamping-jaw having a flat upper face 90 and a lower circular face movably received in said slot and a projection in loose engagement with said lower clamping member arranged movably to retain said clamping jaw in its slot, and means to force and guide said 95 clamping-members towards each other to clamp a tool therebetween.

In testimony whereof, I have signed my name to this specification.

HENRI HALDY.
